[57] CLAIM

The ornamental design for a tire, as shown and de-
scribed.

DESCRIPTION

FIG. 1 is a perspective view of a tire showing my new design, it being understood that the tread pattern is repeated throughout the circumference of the tire, as shown schematically by solid lines;
FIG. 2 is a greatly enlarged plan view of the tread pattern of FIG. 1 showing my new design; and,
FIG. 3 is a side view thereof opposite to the side shown in FIG. 1.
